UNITED STATES PATENT OFFICE.

BARNET I. JOHNSTON, OF LAFAYETTE, INDIANA.

DESIGN FOR A COLLAR-BUTTON.

SPECIFICATION forming part of Design No. 25,697, dated June 30, 1896.

Application filed November 8, 1895. Serial No. 568,366. Term of patent 14 years.

To all whom it may concern:

Be it known that I, BARNET I. JOHNSTON, a citizen of the United States, residing at Lafayette, in the county of Tippecanoe and 5 State of Indiana, have invented and produced a new and original Design for a Collar-Button, of which the following is a specification.

In the accompanying drawings, which show o a collar-button embodying my design, Figure 1 is a side elevation of the button, and Fig. 2 is a top plan view of the same.

My design consists, essentially, of a collar-button having an approximately flat circular 5 base, a circular head of smaller diameter than said base and ellipsoidal in cross-section, and a circular shank which tapers toward the head and is of considerably smaller diameter or cross-section than said head, and

said head having a flat rectangular L-shaped 20 portion which is much narrower than said head extending across and above its upper face, as shown in the accompanying drawings, wherein—

1 represents the base of the button, 2 represents the head of the same, 3 represents the tapering shank, and 4 represents the flat rectangular L-shaped portion of the head.

What I claim is—

The design for a collar-button, made substantially as herein shown and described.

In testimony whereof I affix my signature in presence of two witnesses.

BARNET I. JOHNSTON.

Witnesses:

WILBUR F. SEVERSON,
SAMUEL T. STALLARD.
